(57) **CLAIM**

We claim the ornamental design for a wine cooler, as shown and described.

DESCRIPTION

FIG. 1 is a perspective view of a wine cooler showing my new design.

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines depict portions of the wine cooler in which the design is embodied that form no part of the claimed design. Additionally, the dot-dash lines denote the boundary of the claim and form no part of the claimed design.
